UNITED STATES PATENT OFFICE.

JOHN CONRAD, OF LARCHMONT, NEW YORK.

MANIFOLDING WRITING-TABLET.

1,070,413.

Specification of Letters Patent. Patented Aug. 19, 1913.

Application filed September 12, 1912. Serial No. 720,051.

To all whom it may concern:

Be it known that I, JOHN CONRAD, a citizen of the United States, residing at Larchmont, in the county of Westchester and 5 State of New York, have invented certain new and useful Improvements in Manifolding Writing-Tablets; and I do declare the following to be a full, clear, and exact description of the invention, such as will enable others skilled in the art to which it 10 pertains to make and use the same.

This invention relates to improvements in manifolding writing tablets.

One object of the invention is to improve 15 and simplify the construction of the tablet shown in my allowed United States patent application Serial No. 638,838, filed November 6, 1911, and to provide a positive means for winding the record sheet and projecting 20 the duplicate check sheets or slips from the holder of the tablet.

With this and other objects in view, the invention consists of certain novel features of construction, combination and arrangement of parts as will be more fully described 25 and claimed.

In the accompanying drawings; Figure 1 is a perspective view of my improved tablet; Fig. 2 is a central longitudinal section 30 thereof; Fig. 3 is a plan view of the holder or casing with the cover and top plate, the carbon sheets and the paper supporting plate removed and the sheets of paper forming the duplicate record check in section; Fig. 4 is a cross sectional view taken on the line 4--4 of Fig. 2; Fig. 5 is a similar view 35 taken on the line 5--5 of Fig. 3; Fig. 6 is a vertical longitudinal section taken on the line 6--6 of Fig. 2; Fig. 7 is a bottom plan 40 view of the tablet; Fig. 8 is a detail perspective view of the winding and feeding roller for the record and duplicate check slips; Fig. 9 is a similar view of the combined 45 winding and feeding roller for the supplemental record and duplicate check slips of the additional manifolding mechanism of the bottom or reverse side of the tablet.

Referring more particularly to the drawings, 1 denotes the casing or holder of my 50 improved tablet, said casing being preferably of rectangular oblong form and as being divided by transverse partitions 2 and 3 into roll holding compartments 4, 5 and 6 in which are arranged the paper rolls hereinafter described. In the compartment 4 is secured a bearing frame 7 the side members

of which are recessed and have formed therein bearing sockets 8. Hinged to the inner sides of the casing and adapted to be swung down into the recessed sides of the 60 frame 7 are shaft holding plates 9 which removably hold the ends of the shafts of paper rolls in revoluble engagement with the sockets 8 in the sides of the bearing frame. In the upper edges of the plates 9 are square 65 notches 10 which are provided to receive the ends of carbon paper holding bars herein-after described. Revolubly engaged with the sockets 8 in the sides of the bearing frame 7 are the ends of paper roll supporting 70 shafts 11 which revolubly support the rolls 12 and 13 of the paper forming the duplicate check sheets 14 and 15 which will be hereinafter more particularly referred to.

In the inner portion of the compartment 75 4 and forming part of the partition 2 is a bearing frame 16 the side members of which are bent inwardly at right angles and spaced from the sides of the casing and have formed therein bearing apertures 17 with 80 which are engaged the ends of the shaft 18 containing the roll 19 of paper for forming the permanent or record checks of the tablet. The shaft 18 is further supported by a plate 20 having on its ends upwardly projecting bearing lugs 21 in which are formed notches to receive the ends of the shaft 18.

Over the intermediate compartment 5 is arranged a paper supporting plate 22 the side edges of which are preferably turned 90 up to a slight extent to form paper guiding flanges 23 between which and over the plate 22 the paper from the record roll 19 and the duplicate check rolls 12 and 13 is drawn. The plate 22 also supports the sheets 24 and 95 25 of carbon paper the upper edges of which are secured to the carbon paper holding bars 26 and the ends of which are engaged with the square notches 10 in the shaft holding plates 9 hereinbefore described. The carbon sheets 24 and 25 are arranged respectively between the record check strip and the inner duplicate check strip and between said inner duplicate check strip and the outer duplicate check strip, whereby any 105 writing on the outer duplicate check strip will be impressed or transferred by said carbon sheets to the inner duplicate check strip and the record strip as will be clearly understood. The strips of paper are held in 110 position on the paper supporting plate 22 and the paper rolls and other parts of the

tablet are covered by a cover or top plate 27 having on its side and upper edges right angular flanges 28 which engage the sides of the casing and having on its lower end a 5 curved flange 29 which co-acts with a curved guide plate 30 arranged in the lower end of the casing and having on its outer side triangular lugs 31 which fit into V-shaped notches 32 formed in the outwardly curved 10 lower end of the casing as shown. The curved flange 29 on the lower end of the cover plate overlaps and is spaced a slight distance above the inwardly turned upper edge of the guide plate 30 and forms a slot 15 33 through which the ends of the paper forming the duplicate check slips is brought when drawn from the duplicate check rolls 12 and 13.

Arranged in the lower or end compartment 6 of the casing is a combined record slip winding and duplicate slip feeding roller 34 having on its ends reduced trunnions 35 which are revolvably engaged with the bearing notches 36 in the opposite 25 sides of the casing 1 forming the ends of the compartment 6. On one of the trunnions 35 adjacent to the outer side of the casing is an operating knob 37 by means of which the roller 34 is revolved to wind up the record 30 sheet and to project the duplicate check slips of the tablet. On the opposite end of the roller are a series of ratchet notches 38 with which is engaged the end of a spring pawl 39, whereby the roller is held against retrograde movement. On the roller 34 near its 35 ends are arranged circular paper feeding disks 40 having radially projecting paper engaging pins 41 which engage the strips or sheets of paper forming the duplicate checks 40 and when the roller 34 is turned in the proper direction will unwind said strips from their respective rolls and draw the same across the plate 22 which operation projects the ends of the check sheets through 45 the slot 33 to the desired extent whereupon said strips may be readily torn off against the projecting edge of the curved flange on the end of the cover plate 27 as will be readily understood.

50 The roller 34 is preferably formed in separable sections 42 and 43. The section 43 is of substantially cylindrical form having one side cut away or reduced as shown. The section 42 of the roller is in the form of a segmental plate which is adapted to fit into close engagement with the recess or cutaway portion of the section 42 and to form a flush engagement with the larger portion of this section, whereby when said sections of 55 the roller are in operative engagement a smooth cylindrical surface is provided. The inner or free end of the section 42 of the roller is slightly reduced and when said sections are brought together said reduced end 60 is adapted to fit into a socket 44 formed in

the adjacent end of the section 43. The section 43 has on its opposite end a stud 45 which is adapted to be engaged with a socket 46 in the adjacent end of the section 42, whereby this end of the section 43 is held in 70 engagement with the section 42. By constructing and arranging the roller 34 in separable sections as shown and described, the end of the sheet of paper forming the record checks may be clamped between said 75 sections of the roller and thus readily and securely fastened to the latter. When the roller 34 is in position in the compartment 6 the trunnions of the roller are held in revolvble engagement with the bearing notches 38 by lugs 47 formed on the inner surfaces of the adjacent portions of the side flanges of the top or cover plate of the casing. On the inner side of the end of the cover plate above the slot 33 are secured 80 curved springs 39 which bear against the upper inwardly curved edge of the guide plate 30 and yieldingly hold the latter in position in the end of the casing of the tablet.

85 In the central compartment 5 near one side of the casing is arranged a roll of paper 48 on which additional checks may be written for supplemental orders given after the original checks have been made out and removed from the tablet. The roll of paper 48 is supported on a shaft 49 one of the trunnions of which is mounted in a bearing aperture in the partition 3 while the other end of the shaft is removably engaged with a bearing notch 50 formed in the partition 90 3. This end of the shaft is held in revolvble engagement with the notch 50 by a spring keeper plate 51 which is secured to the bottom of the casing and has therein an aperture with which the reduced end of the shaft 49 is engaged. When it is desired to remove the shaft the keeper plate may be sprung back out of engagement with the end of the shaft after which the same may be 100 readily removed from the notch 50 and the bearing aperture in the partition 3.

105 Removably arranged in the compartment 5 is a bearing frame 52 having on its lower side a paper supporting plate 53 which when the frame 52 is in position forms a support for the paper forming the supplemental checks as will be hereinafter more fully described. Revolvably mounted in the sides of the frame 52 is a shaft 54 on which 110 is arranged the roll of paper 55 for forming the supplemental record checks of the tablet. The sheet of paper from the roll 55 passes over the outer surface of the paper supporting plate 53 and between the same and the sheet for the duplicate checks from the roll 48 and said record sheet from the roll 55 is adapted to be wound upon a combined record receiving and duplicate check feeding roller 56 arranged in the compartment 2 adjacent 115

to the opposite side thereof from that in which the roll of paper 48 is arranged.

The roller 56 has its ends reduced to form journals 57 which are revolubly engaged with bearing notches 58 formed in the partitions 2 and 3 and on the ends of the roller are annular check feeding disks 59 having thereon series of radially projecting paper engaging pins 60 which are adapted to engage the sheet of paper from the roll 48 and which form the duplicate supplemental checks. By thus constructing and arranging the roller 56 it will be seen that when the latter is revolved the sheet will be unwound from the roll 55 and wound upon the roller 56 thus retaining the supplemental record checks of the tablet. Simultaneously with the winding of the record checks on the roller the feeding disk and pins 60 coming into engagement with the sheet from the duplicate supplemental record roll 48 will unwind said sheet from this roll and feed the outer end thereof through a slot 61 formed between the lower edge of a recess 25 in one side of the casing 1 and the lower edge of the adjacent side flange 28 of the top plate. The portion of the flange 28 opposite the recess in said side plate is extended downwardly below the edge of the recess 30 in the side piece of the casing, said edge of the recess being bent downwardly to form a plate 62 on which the projecting portion of the sheet forming the duplicate supplemental checks may be readily torn off. The body of the roller 56 is preferably formed in two sections which are constructed and arranged similarly to the sections of the feed roller 34 and between said sections is firmly clamped the end of the sheet from the roll 48 containing the paper for the supplemental record checks.

The roller 56 has fixedly mounted on one end a milled operating wheel 63 which is disposed adjacent to one side of the partition 2 and has its edge projecting through a slot 64 in the adjacent side of the casing 1, said projecting edge of the wheel being adapted to be engaged by the thumb or finger and the roller thereby turned to project and wind up the sheets of paper as hereinbefore described. Secured to the inner side of the partition 2 is a spring pawl 65 which engages the teeth of the wheel 63 and holds the latter against retrograde movement.

Between the supplemental record sheet and the supplemental check sheet from the rolls 55 and 48 is arranged a sheet of carbon paper 66, whereby the writing on the supplemental check sheet from the roll 48 is impressed or transferred to the record sheet from the roll 55. The carbon sheet 66 is secured at one end to a retaining rod 67 one end of which is engaged with the aperture in the partition 3 while the other end is engaged with an obliquely disposed notch 68

in the partition 2. The rod 67 is held in operative engagement with the aperture and notch in the partitions 2 and 3 by a spring finger 69 formed on a plate 70 secured to one side of the partition 2, said spring finger 70 corresponding in shape to and is disposed over the notch 68 and in engagement with this end of the rod 67 as shown. In order to permit the supplemental checks to be written on the supplemental check sheet 75 from the roll 48, a rectangular opening 71 is formed in the bottom or lower side of the casing over the paper supporting plate 53 which is secured to the frame 52 and is disposed adjacent to the inner side of the bottom of the casing as hereinbefore described. The plate 53 is held in position to support the sheets from the rolls 48 and 55 by a transversely disposed bracing plate 72 which has its upper edge secured to the inner surface of the paper supporting plate 22 and its outer ends engaged with the notches 74 in the bearing frame 52 to which said plate 53 is secured. On the inner side of the partitions 2 and 3 are lugs 75 which engage the bearing notches 58 in which the journals 57 of the roller 56 are mounted, said lugs thus holding the roller in revoluble engagement with said bearing notches.

Having thus described my invention, what I claim is:

1. A writing tablet of the character described comprising a casing having therein transverse partitions, whereby the casing is divided into a plurality of compartments, bearing frames arranged in said compartments, paper holding shafts revolubly mounted in said bearing frames and carrying rolls of paper adapted to be unwound from said shafts, means to hold said shafts in revoluble engagement with said frames, paper supporting plates arranged in the casing and adapted to support the sheets of paper unwound from said rolls while said sheets are being written upon, sheets of transfer paper arranged between the sheets from said rolls, retaining rods arranged in said compartments and secured to one end of said transfer sheets and whereby said transfer sheets are held in operative position, additional winding rolls revolubly mounted in said casing and adapted to receive sheets of paper from certain of said paper rolls to form a record of checks written on the sheets from the other paper rolls, means on said rollers to engage the sheets from said other paper rolls, whereby said sheets are positively fed from the casing, and operating devices on the ends of said rolls, whereby the latter are turned.

2. A manifolding writing tablet of the character described comprising a casing, transverse partitions arranged therein to form a series of roll holding compartments, bearing compartments arranged in one of

4. said frames and having therein bearing notches, roll supporting shafts revolvably and removably engaged with said notches and carrying rolls of paper adapted to be unwound therefrom to form duplicate check and record sheets, shaft retaining plates to hold said shafts in revolvble engagement with the notches in one of said frames, said plates having therein notches, transfer sheet holding rods engaged with said notches, transfer sheets secured to said rods and arranged between the record and check sheets drawn from said paper rolls, a plate adapted to form a support for said sheets, and a combined paper winding and feeding roller adapted to receive and wind up said record sheet and to project said duplicate check sheets across said supporting plate.

3. A manifolding writing tablet comprising a casing, paper holding shafts revolvably mounted therein and carrying rolls of paper adapted to be unwound therefrom to form record and duplicate check sheets, a combined record sheet winding and check sheet feeding roller revolvably mounted in one end of said casing, said roller comprising a cylindrical section having on one side a recess and in one end a socket, a segmental section adapted to fit the recess in said cylindrical section and having a socket to receive the inner end of said cylindrical section, a stud on said segmental section to engage the socket in the end of said cylindrical section, whereby the end of said record sheet is secured between the sections of said roller, sheet projecting disks carried by said roller and having thereon pins to engage and project said check sheets, ratchet notches on one end of said roller, a pawl to engage said notches and hold said roller against retrograde movement, and an operating member on the opposite end of said roller.

4. A manifolding writing tablet comprising

ing a casing having in its bottom an opening, transverse partitions arranged therein to divide said casing into intermediate and end compartments, paper holding shafts revolvably mounted in one of said end compartments and carrying rolls of paper adapted to be unwound therefrom to form record and duplicate check sheets, a combined paper winding and projecting roller revolvably mounted in the other end compartment of the casing and adapted to receive and wind thereon said record sheet and to project said check sheets, a paper supporting shaft in one end of said intermediate compartment and having its ends revolvably mounted in the partitions of the casing, said shaft carrying a roll of paper adapted to be unwound therefrom to form a supplemental check sheet, a bearing frame arranged in said compartment, a paper supporting plate secured to said frame adjacent to the inner side of the bottom of the casing over the opening therein, a paper holding shaft revolvably mounted in said frame and carrying a roll of paper adapted to be unwound therefrom and passed across said supporting plate and between the same and said check sheet to form a record sheet, a transfer sheet between said check and record sheets, a combined record sheet winding and check sheet feeding roller revolvably mounted in said intermediate compartment, and an operating member on said roller, said member projecting through the side of said casing.

In testimony whereof I have hereunto set my hand in presence of two subscribing witnesses.

JOHN CONRAD.
